UNITED STATES PATENT OFFICE.

SAMUEL TIMOTHY MICKEY, OF WINSTON SALEM, NORTH CAROLINA.

STOVEPIPE-JOINT.

No. 851,298.

Specification of Letters Patent.

Patented April 23, 1907.

Application filed May 8, 1906. Serial No. 315,800.

To all whom it may concern:

Be it known that I, SAMUEL TIMOTHY MICKEY, a citizen of the United States, residing at Winston Salem, in the county of Forsyth and State of North Carolina, have invented a new and useful Stovepipe-Joint, of which the following is a specification.

This invention relates to pipe joints more particularly to the joints between stove pipes and the thimbles in chimneys, and has for its object to simplify and improve the construction and increase the efficiency of devices of this character.

With these and other objects in view which will appear as the nature of the invention is better understood, the invention consists in certain novel features of construction as hereafter fully described and claimed.

In the accompanying drawings forming a part of this specification and in which corresponding parts are denoted by like designating characters is illustrated the preferred form of the embodiment of the invention capable of carrying the same into practical operation it being understood that various changes in form, proportions and minor details of construction may be resorted to without departing from the principle or sacrificing any of the advantages of this invention within the scope of the appended claims.

In the accompanying drawings:—Figure 1 is a sectional view of a portion of a chimney, the stove pipe thimble, and a portion of a stove pipe coupled to the thimble by the improved devices. Fig. 2 is a perspective view of the thimble detached. Fig. 3 is a perspective view of a portion of the stove pipe detached. Fig. 4 is a sectional view on a reduced scale, illustrating the manner of applying the improved device to the thimble cap.

The improved device may be readily adapted to the joints of pipes of various kinds, but is more particularly applicable to the joints between stove pipes, and the joints between stove pipes and the thimbles of the chimney, and for the purposes of illustration is shown thus applied, the chimney being represented at 10, the thimble, which is the receiving tubular member, at 11, and the pipe, which is the entering tubular member, at 12.

The thimble or receiving member is of the usual form except that it projects for a short distance from the plaster line, represented at

13 and is provided with an annular flange 14 spaced a short distance from the outer face of the plaster. The flange 14 is formed with one or more gaps or spaces 15 and the thimble is provided with an inwardly extending pin 16 intermediate the ends. 55 60

The stove pipe or entering member 12, is provided with hooks 17 corresponding to the gaps 15 in the flange 14 and adapted to pass through the same when the pipe is inserted into the thimble, and when the pipe is thus inserted and rotated, the hooks 17 will pass over the solid portions of the flange and firmly lock the pipe to the thimble. Extending from the end of the pipe 12 is a hook 18 adapted to engage the pin 16 when the hooks 17 have passed over the flange, to prevent the pipe being turned too far, and also to serve as an additional holding means, to prevent the withdrawal of the pipe. 65 70 75

The device is readily applicable without structural changes or material modifications, to the joints between stove pipe sections, and may also be applied to the caps employed for closing the thimbles when the pipes are removed, as illustrated in Fig. 4. 80

The device is simple in construction, can be inexpensively manufactured and applied to pipes of all sizes.

The pipe is firmly locked in position, and effectually prevented from accidental displacement and also from being thrust too far into the thimble. 85

Having thus described the invention, what is claimed, is:—

In a device of the class described, a tubular receiving member having a stop pin and a flange provided with one or more openings, and a tubular entering member having radial hooks and a projecting hook, the parts being so arranged that when said entering member is inserted into the receiving member and rotated, the radial hooks will pass through the flange openings and engage the flange and the projecting hook will engage the stop pin. 90 95 100

In testimony that I claim the foregoing as my own, I have hereto affixed my signature in the presence of two witnesses:

SAMUEL TIMOTHY MICKEY.

Two witnesses:

EDWARD T. MICKEY,
W. H. CLINARD.
